UNITED STATES PATENT OFFICE.

DOMENICO MOLINARI, OF BROOKLYN, NEW YORK.

BOTTLE STOPPER AND MEASURING GLASS.

1,419,580.

Specification of Letters Patent. Patented June 13, 1922.

Application filed August 23, 1920. Serial No. 405,223.

To all whom it may concern:

Be it known that I, DOMENICO MOLINARI, a citizen of the United States, residing at 2340 Pacific Street, in the borough of Brooklyn, county of Kings, city and State of New York, have invented a new and useful Improvement of a Bottle Stopper and Measuring Glass, of which the following is a specification.

10 The objects of my invention are to provide, as a new and improved article of manufacture, a new and improved combined bottle stopper and measuring glass which may also be used as a drinking cup. It may 15 be made of any suitable size and shape, to be used as a stopper for receptacles of all shapes and sizes of the bottle or jar type; and while the same may be made of other materials, in the usual and most preferred 20 form it is constructed of transparent, or at least translucent, glass, etc.; and is usually brought to form by blowing in a mold while in a plastic molten state, in the manner well known in the art of glass-working.

25 My said invention is fully shown and described in the following specification, of which the accompanying drawing, comprising a single figure, forms a part; wherein is shown in central vertical section, the top 30 portion of a bottle of ordinary shape, etc., having one of my improved measuring stoppers in the bottle-stopping position in the mouth thereof.

As shown in said figure, in the particular 35 form of embodiment shown, my said improved combined bottle-stopper and measuring glass, is composed of a hollow, substantially cylindrical main-body or base portion A, having a flat outer surfaced integrally 40 formed end-plate B, closing the same at one end, generally and usually of sufficient thickness, and weight, to hold the same against accidental over-turning when used as a measuring-glass, and supported by such 45 outer flat surface upon a table or other suitable like support. And in this particular form, the main-body cylindrical portion A, merges by the gradually converging central cylindrical wall portion C, with the stopper- 50 portion D, tightly fitting within the orifice of the bottle-neck E, formed integral with the bottle-body F; such neck-orifice and the stopper-portion D, being usually each of the 55 gradually diminishing diametered form shown, and such stopper-portion D, being

usually and preferably ground into tight fitting connection with the wall of the neck-orifice, in the manner well known in positional grinding in of ground-glass stoppers of the well known solid form; and such 60 stopper-portion D, is usually and preferably provided at its extreme outer open mouth and, with an inwardly extending annular strengthening ring or bead G.

Carried at suitable intervals by the peripheral wall of such combined stopper and measuring glass, and usually but not necessarily extending entirely around the same, are a number of measuring-lines showing the capacity of the device when used as a 65 measuring-glass, and filled up to such line, when held with the open mouth at G, upward; and in this case the measurements are indicated reading from the bottom, merely by the fractions and numerals shown, viz: 70 $\frac{1}{4}$, $\frac{1}{2}$, $\frac{3}{4}$, 1 and 2, which, according to the size of the chamber of the stopper may mean, tea-spoons, table-spoons, drams, which measuring lines and numerals may be formed in or on the glass surface by etching, 75 or by being blown exteriorly in the glass in the process of formation, as I have indicated only however as to the line marked 2, as shown at H. And as the ground-glass stopper-surface should not be marred by words 80 placed thereon, to indicate the full capacity of the stopper-glass, words such as "Level full equals 4" may be placed on the stopper, as shown at C; but all such measurements and lines shown, are of course, only 85 tentative, and are shown in the drawing, as reversed, for better showing of the idea; and I do not intend to limit myself to any particular form of indicating marking for measurements, as any such marking I consider to be 90 within the broad scope of my invention.

Neither do I intend to limit myself to a ground-in stopper, nor to one in which the stopper fits within the bottle-neck orifice, as the stopper may be located exterior to the bottle-neck, and be ground or not ground to fit, as may be desired, and still be within the scope of my invention, as I do not limit myself to the exact form of construction shown.

I claim;

1. The combination with a bottle, of a stopper therefor, said stopper comprising a substantially cylindrical hollow glass receptacle open at the end to be inserted in the bottle thereby providing a rim, and having 110

the exterior wall thereof adjacent the rim the body portion being provided with graduations.

2. A bottle stopper comprising a substantially tubular glass receptacle open at the end to be inserted in the bottle thereby providing a rim, the rim portion of the receptacle being ground to fit a bottle neck, and

DOMENICO MOLINARI.
